US00D729247S

(12) **United States Design Patent**
Hackett et al.

(10) **Patent No.:** **US D729,247 S**
(45) **Date of Patent:** **** May 12, 2015**

(54) **MOBILE COMPUTER**

(71) Applicant: **Symbol Technologies, Inc.**,
Schaumburg, IL (US)
(72) Inventors: **Edward Hackett**, Surbiton (GB); **Mark Fountain**, London (GB); **Nickolas Ovvadias**, Abingdon (GB); **Jorg Schlieffers**, Marcham (GB)

(73) Assignee: **Symbol Technologies, Inc.**, Holtsville, NY (US)

(**) Term: **14 Years**

(21) Appl. No.: **29/492,276**

(22) Filed: **May 29, 2014**

(51) **LOC (10) Cl.** **14-02**

(52) **U.S. Cl.**

USPC **D14/426**

CLAIM

The ornamental design for a mobile computer, as shown and described.

DESCRIPTION

FIG. 1 is a front perspective view of an ornamental design for a mobile computer;

FIG. 2 is a rear perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

The broken lines and unshaded portions contained within broken lines are not claimed.

1 Claim, 7 Drawing Sheets
